TELEPHONE ANSWERING AND RECORDING APPARATUS

John J. Shively and Harry R. Van Deventer, New York, N. Y., assignors, by mesne assignments, to Peatrphone Corporation, Sumter, S. C., a corporation of Nevada

Application May 4, 1940, Serial No. 333,268

49 Claims. (CL. 179—6)

This invention pertains to improvements in telephone answering and recording apparatus.

An object of the invention is to provide means operable automatically upon the ringing of a telephone to answer the telephone and to record any message received therethrough.

Another object is to provide a device of the character described requiring no acoustic connection with the telephone bell.

Still another object is to provide a device of the above type including means adapted to automatic cyclic carrying out of the various normal functions.

Still another object is to provide a device which is simple, low in cost, readily manufactured, readily installed and easily placed in proper operation by inexperienced persons.

Another object is to provide apparatus of the character described employing cheap records of standard type.

A further object is to provide means by which any desired speech may be delivered by the machine in answering the telephone.

Still another object is to provide a device of the character described including means to restore the telephone circuit to normal in case of failure of the current supply, and means operable thereafter upon restoration of current to maintain the telephone disconnected while the cyclic operation of the device restores the latter to normal starting condition.

A further object is to provide a device of the character described adapted to the carrying out of various supplementary functions such as receiving dictation, recording office instructions, and the like.

Other objects and advantages of the invention will become evident during the course of the following description in connection with the accompanying drawings, in which

Figure 1 is a side view of the main operating mechanism in partial joggled section;

Figure 2 is a detail view of the releasing latch mechanism in normal operating position;

Figure 3 is a similar view of the same released by current failure;

Figure 4 is a plan view of the device with the top cover removed;

Figure 5 is a front elevation of the main operating device with the telephone removed and the phone switch control arm in non-operative position;

Figure 6 is a vertical side sectional view of the detector mechanism;

Figure 7 is a front elevation of the same;

Figure 8 is a plan view of the automatic cyclic control mechanism including the lower or speaking turn-table and related parts;

Figure 9 is a front elevation of the same;

Figure 10 is an enlarged detail view of the answering speech control mechanism in operating position;

Figure 13 is a similar view of the switching cam mechanism;

Figure 14 is a detail view of the telephone control cam;

Figure 15 is a similar view of the answering speech control cam and lever;

Figure 16 illustrates in section the signal switch, the relay circuit breaker and the automatic change-over switch, the latter two being taken on the section 16—16, Figures 17 and 18 respectively;

Figure 17 illustrates an automatic change-over switch taken in section 17—17, Figure 16;

Figure 18 is a longitudinal sectional view of the relay circuit breaker in the plane 18, Figure 16;

Figure 19 is a detail view of the recorder arm locating means with the recorder arm in recording position;

Figure 20 is a similar view with the recorder arm in raised position;

Figure 21 is a polar diagram setting forth the successive operations of the automatic cycle, and

Figure 22 is a wiring diagram of the entire device.

Referring to Figure 1, the numeral 30 generally denotes the main answering and recording unit having a casing 31 which may be provided with a hinged cover 32. The front of the casing

31 is preferably inclined and has removably fastened thereto a plate 33 in which are secured cup-shaped receptacles 34 and 35, Figures 1, 4 and 5. The cups 34 and 35 are made of any suitable material, preferably rubber or the like having sound insulating properties, and are spaced apart a distance approximately equal to the center distances of the transmitter and receiver of a standard telephone hand-set. A speaker 36 and a microphone 37, Figures 5 and 1, are mounted in the bottoms of cups 34 and 35 respectively.

Raised brackets 38 and 39, secured to the plate 33, are adapted to support a telephone hand-set 40 so that the transmitter 41 and receiver

42 thereof rest within the mouths of the cups 34 and 35 adjacent the speaker 36 and microphone 37 respectively. The upper inner diameters of the cups 34 and 35 are larger than those of the telephone transmitter 41 and receiver 42, so that the latter rest therein with substantial clearance as shown in Figures 1 and 4.

Answering speech and cyclic control mechanism

An inverted U shaped supporting plate 43, Figures 1, 8 and 9, is secured in the lower part of the casing 31 and has fastened thereto a small gear-box 44. A vertical shaft 45, journaled in the box 44, carries on its upper end a turn-table 46 adapted to support and drive a record 47. The turn-table 46 may be driven by a motor 48, Figures 8 and 9, in any suitable manner, for example via a rim-driving intermediate roller 49, Figure 8. As such drives are well-known in the art, no further description thereof is necessary.

An elongated extension 50 of the gear box 44, Figure 9, has journaled therein a cam-shaft 51 which is driven through a worm-gear 52, Figure 1, by a worm 53 on the vertical shaft 45. The shaft 51 carries four cams 54, 55, 56 and 57, hereinafter described in greater detail.

The cam 54 has a spiral lobe 58, as shown in Figure 12. A forked rod 59, longitudinally guided on the shaft 51, carries a pin 60 riding on the periphery of the cam 54. The rod 59 is pivoted to the short arm of a bell crank 61, Figure 1. The longer arm 62 of the bell crank extends outward through a slot 63 in the front of the casing 31, Figures 4 and 5, and terminates in a pointer 64 cooperative with an exterior scale or dial 65. It will be evident that as the cam 54 revolves clockwise, Figure 12, and the pin 60 rides up the lobe 58, the bell crank 61 is rocked clockwise and the pointer 64 is moved upward along the scale 65 until the pin over-rides the tip of the lobe 58, whereupon the pointer 64 is returned to its lower position by gravity.

The cam 55, Figure 13, hereinafter termed the switch cam, has a periphery comprising two circumferential portions 65 and 66 of different radii, the radius of arc portion 65 being greater than that of arc portion 66.

An insulated pin 67, secured in and protruding from the rear side of the cam 55, is adapted to engage and momentarily open a small breaker 68, shown in detail in Figures 16 and 18. A similar pin 69 is adapted to engage and momentarily close a normally open switch 70, shown in detail section in Figure 16.

The numeral 71, Figure 16, generally denotes a gang-switch comprising three double-throw switch units 72, 73 and 74. The switches 72, 73 and 74 have central arms 75, 76 and 77 respectively, all secured in a common shaft 78 which is preferably of insulating material. The constructions of the three switches are substantially identical, Figure 17 showing typically the structure of switch 72 in which the central arm 75 is adapted to complete circuits either through an upper contact point 79 or a lower contact point 80.

A tappet arm 81, Figures 13 and 16, is secured to the gang-switch shaft 78 and rides on the periphery of cam 55. A torsion spring 82, Figure 16, urges the arm 81 upward and throws the central arms 75, 76 and 77 into engagement with their upper contact points when the arm 81 is in engagement with the cam portion 66, but in normal position, as shown in Figure 13, the larger radial portion 65 of cam 55 holds the arm 81

down and the switches in lower contact engagement.

The cam 56, Figure 14, has in its periphery a notch 83. A transverse rocker shaft 84, Figures 1, 9 and 14, is journaled in lugs 85 and 86 on the upper mounting portion 87 of the gear-box 44 and has secured on one end a short lever 88 which carries a roller 89 engaging the cam 56. In normal or stop position the roller 89 rests in the notch 83 as shown in Figure 9, but when the cam starts its clockwise rotation the roller is forced out of the notch, thereby rocking the lever 88 and shaft 84 clockwise. A torsion spring 90, coiled around the shaft 84 as shown in Figure 9, urges the roller 89 against the cam 56.

A downwardly extending lever 91, Figures 1 and 9, is secured to the inner end of the rocker shaft 84.

Referring to Figure 1, the numeral 92 denotes a channel-shaped lever pivoted at 93 in the front of the casing 31. An arm 94, hereinafter referred to as the switch control arm, is also swung on the pivot 93 and extends outwardly through an opening 95 in the casing 31. The outer end of the arm 94 comprises a weighted cross member 96, Figures 1, 4 and 5, adapted to engage and normally depress the switch control member 97 of the main telephone unit 98. A set screw 99 in a lug 100 on the bottom of the arm 94 bears against the lever 92 and is adjustable inwardly and outwardly to vary the normal vertical position of the weighted member 96.

A magnetic latch 101, Figures 1, 2 and 3, is secured to lower end of the channel lever 92. The latch 101 comprises an angle frame 102, an electro-magnet 103, and an armature 104 pivoted at 105 to the inwardly extending foot 106 of the frame 102. The lower end of the armature 104 extends through the foot 106 to form a short detent 107.

A finger 108, pivoted to the lever 91, is urged upward by a spring 109 so that the tip 110 of the finger normally rests against the bottom of the foot 106 behind the detent 107 as shown in Figure 1. When the magnet 103 is energized it holds the armature 104 locked against its face, so that when the shaft 84 and lever 91 are rocked clockwise as previously described, the tip 110 of finger 108 engaging the detent 107 swings the channel lever 92 forward as shown in Figure 2 to raise the arm 94 and cross member 96, the latter as shown in dot-and-dash lines in Figure 1. If while the parts are in this position the magnet 103 is de-energized it releases the armature 104, causing the detent 107 to rock outward and release the finger tip 110, as shown in Figure 3, allowing the weighted member 96 of the arm 94 to fall and swing the lever 92 inward to normal position against stationary stop 111. A light torsion spring 104A is provided to return the armature 104 to normal position. It is evident that when the finger 108 has been released by the detent 107 as described above, the tip 110 cannot re-engage the rear of the detent until complete rotation of the cam 56 has allowed the lever 91 to retract the finger 108 to normal position as shown in Figure 1. The purpose of the foregoing arrangement will be hereinafter explained during the description of the general operation of the machine.

A small horizontal arm 112 on the arm 91, Figure 1, is adapted to engage and actuate a normally open push switch 113 of any suitable type when the shaft 84 is rocked clockwise.

A phonograph arm 114, Figures 1, 8, 9, 10 and

11, is vertically pivoted on the usual swivel support 115 secured to the plate 43. The arm 114 is equipped with a reproducer or pick-up 116, Figure 1, of any suitable type employing a needle 117 and adapted to cooperate with the record 47. A small cross member 118, secured in the under portion of the arm 114, as shown in detail in Figures 10 and 11, has a downwardly extending rigid finger 119. A lift lever 120, pivoted at 121 to a supporting bracket 122 on the plate 43, Figure 8, has a plurality of inclined notches 123, 123A, etc., adapted to underlie the finger 119. The inner end of the lever 120 carries a pin 124 which rides on the periphery of the cam 57, hereinafter referred to as the speech control cam.

Referring to Figure 15, it will be seen that the cam 57 comprises a circumferential portion 125 of radius smaller than the remaining portion 126, the pin 124 normally resting on the larger portion 126 and thus holding the lever 120 inclined upward as shown in Figure 15. When the lever is thus raised, it engages the finger 119 to hold the reproducer arm 114 sufficiently elevated that the needle 117 is clear of the record 47 as shown in Figure 1. In this raised position, due to the angularity of the notches, for example notch 123 as shown in Figure 11, the finger 119 rests in the right-hand or outer corner of the notch. When the cam 57 revolves and the pin 124 rides down to the reduced cam portion 125, the lever 120 lowers the arm 114 to bring the needle 117 into engagement with the record 47, and due to the fact that the finger 119 is definitely positioned in notch 123 as noted above, the point of engagement of the needle on the record is accurately determined. The duration of the engagement, as determined by the reduced cam portion 125, is so proportioned to the cross feed of the rotating record that the arm 114 is again lifted by the lever 120 before the finger 119 can overrun the inner slope of the notch 123. Consequently, at each cyclic rotation of the cam 57 the needle 17 is brought into engagement with and allowed to traverse a definite zone on the record, this zone being illustrated at 127 in Figure 8. When the cam again raises the reproducer, the finger 119 in being lifted slides down the slope of the notch 123 into initial position. Similarly, if the finger 119 is placed in the notch 123A, each cyclic operation causes the needle 117 to traverse a second pre-determined zone 127A, Figure 8 on the record 47, and the same applies to each of the other notches, each notch controlling the pickup to repeatedly play throughout its particular zone on the record.

Referring to Figure 9, a transverse strip 128 which supports the gang-switch 71 and breaker 68, also carries a normally closed single break contact relay 129 and a relay 130, to make three sets of contacts and break one set, these being standard devices shown in electrical detail in the wiring diagram, Figure 22. A thermal relay 131 having a bimetallic arm 131A is mounted on an insulating base 132 on the support 128. The arm 131A is adapted when heated to bend into contact with an adjustable contact screw 133. A small heating coil 134 surrounds the arm 131A, the electrical connections of these devices also being shown in detail on the wiring diagram Figure 22 and hereinafter described.

Recording mechanism for incoming speech and play-back

Referring to Figure 1, a platform or board 135 is secured in the upper part of the casing 31. A

second gear-box 136 attached to the platform 135, rotatably supports a second vertical shaft 137 carrying an upper turn-table 138 which is adapted to be rim-driven by a motor 139 in any suitable manner as set forth with respect to lower turn-table 46.

An outwardly extending shaft 140, journalled in the second gear-box 136 and driven therein through suitable worm-gearing (not shown) by the shaft 137, terminates in a lead screw 141.

A recording or cutter arm 142, preferably of inverted channel shape, is swung on a transverse pivot 143 in the head 144 of a hollow swivel 145 and carries in its forward end a recorder or cutter head 146, the cutter head being mounted in any suitable manner permitting limited vertical movement in the arm, such mountings being well known in the art and therefore requiring no further description herein.

The side members 147 of the arm 142 extend downward through a clearance opening 148 in the board 135 and are directed forward and secured together thereunder to form a feeding arm 149, Figure 1. The arm 149 terminates in a downwardly directed knife edge 150 adapted to engage the thread-grooves of the lead screw 141. It will be understood that when the cutter arm 142 is rocked upward, the knife edge 150 clears the screw 141 to allow the arm to be swung manually to various positions over the record blank 159.

An upright bracket 151 secured to the top of the platform 135 below the recorder arm 142 has horizontally pivoted thereon a shoe 152 provided with a small handle 153, these parts being shown in place in Figures 1 and 4 and in cross sectional details in Figures 19 and 20. The shoe 152 has a smooth rear edge 154 and a plurality of spaced notches 155, 155A, etc., in its front edge. A light torsion spring 156, Figures 19 and 20, urges the shoe clockwise. When the recorder arm 142 is lowered into recording position the smooth rear edge 154 of the shoe 152 is pressed lightly against the bottom of the inner side member 147. In this position, due to the lightness of the spring pressure and the smoothness of the rear shoe edge 154, the latter offers no resistance to the cross feed of the arm 142 in recording. However, when the arm 142 is raised, the spring 156 swings the shoe 152 back over center against a stop 157 as shown in Figure 20. In this position the shoe 152 forms a support for the arm 142 which prevents the latter from being accidentally dropped so as to bring its cutting needle or stylus 158 violently against the record blank 159. When it is desired to set the cutter needle in engagement with the record blank, the shoe 152 is swung forward by means of the handle 153, allowing the cutter to be lowered easily and accurately. Prior to lowering the cutter, the side member 147 may be set in any desired one of the notches 155, 155A, etc. These notches are so located and spaced as to guide the stylus 158 into engagement with the record blank at points corresponding to the outer limits of the zones 127, 127A, etc., of the lower record 47, for purposes hereinafter set forth. When the arm 142 is swung clear of the record blank into non-operating position in Figure 1 and in dot-and-dash lines, Figure 4, its side member 147 rests in a deep notch 160 in the shoe 152, and a stationary spring clip 161 may be provided to hold the arm in this position.

A second hinged reproducer arm 162, herein-after termed the playback arm, is swivelled at 163

in the usual manner and carries a reproducer or pickup 164 similar to the lower pickup 118, the pickup 164 being adapted to cooperate with the upper record blank 159 after recordings have been made thereon.

The numeral 165, Figure 4, indicates a volume control potentiometer, shown electrically in Figure 22. A three position four-pole manual switch 166, Figure 1, also shown in electrical detail on the wiring diagram, Figure 22, is equipped with an indicating knob 167, Figure 4, cooperative with a dial 168.

An amplifier 169 of any suitable type, is mounted in the bottom of casing 31 as shown in Figure 1. A normally open push button switch 170 is located in the upper platform 135. The master switch 171 and a tell-tale bull's eye lamp 172 are secured in the front of the casing 31 as shown in Figures 4 and 5.

A normally closed push switch 173, Figures 1 and 4, hereinafter termed the limit switch, is secured to the bottom of platform 135 in position to be engaged and opened by the feeding arm 149 as it reaches the inner limit of its travel along the feed screw 141.

A flexible current supply cord comprising twin conductors 174 and 175, Figures 4 and 5, and adapted to be connected to any suitable source of current, leads into the lower part of the casing 31.

Signal detecting mechanism

A second flexible cord comprising light twin conductors 176 and 177, Figure 4, leads from the casing 31 to a detector, interrupter or signal pickup 178 adapted to be attached to the telephone bell box 179 in a suitable manner, such as by a rubber suction cup 180. The usual telephone cords 181 and 182 connect the telephone unit 98 with the bell-box 179 and hand-set 48 respectively.

The detector 178, shown in enlarged detail in Figures 6 and 7, has a flat insulating plate 183 secured to the suction cup 180 or equivalent fastening means. A transverse contactor bar 184, suspended through an upright central rod 185 from a small eye-bolt 186, normally rests across two contact members 187 and 188, the latter members being connected to the conductors 176 and 177 respectively.

Referring to the wiring diagram, Figure 22, the supply conductor 175 is connected directly to a current supply trunk conductor 189. The supply conductor 174 is connected through the master switch 171, a wire 190, the normally closed limit switch 173, and a short lead 191 to a second current supply trunk conductor 192.

Starting circuit

The primary winding 193 of a transformer 194 is connected between the trunk conductors 189 and 192. The secondary winding 195, which is of low potential such as six volts, is connected on one side via the conductor 176 to the contact member 187 of detector 178. The other side of the secondary 195 is connected via a wire 196 to the normally closed relay 129, which in turn is connected through the conductor 177 to the detector contact member 188.

It will be evident that when the transformer 194 is energized and the detector bar 184 lies on the contact members 187 and 188, a closed circuit exists through the relay 129, causing the movable contact arm 197 thereof to be held clear of its fixed contact point 198 against the urge of the closing spring 199.

The movable contact arm 197 is connected to the trunk conductor 192. The fixed contact point 198 is connected to one side of the heating coil 134 of thermal relay 131, while the other side of the coil 134 is connected through a branch lead 134A and a manual switch 263 to a contact point 134B normally engaged by one movable contact arm 203 of the relay 130. The arm 203 is connected by leads 204 and 205 and the switch 68 with the trunk conductor 189.

The bimetallic contact arm 131A is also connected through a branch 131B to the trunk conductor 189. This arm normally stands clear of the adjustable contact 133, but when sufficiently heated is adapted to bend into engagement with the latter. Leads 200 and 201 connect the contact 133 to one side of the three-pole relay 130, the other side of 130 being connected via a branch 202 to trunk conductor 189. One movable contact arm 203 of relay, as noted above, is electrically joined via lead 204, the normally closed switch 68, Figures 16 and 18, and lead 205 to the trunk conductor 189, while the corresponding fixed contact point 206 is connected to the relay lead 201. Thus when the thermal contact arm 131A engages the point 133, the relay 130 is thrown in circuit across trunk conductors 189 and 192 and as the relay is energized it closes the arm 203 on the contact point 206, establishing a second or holding connection to the trunk conductor 189, so that after the thermal arm 131A breaks its contact the relay 130 remains closed until its above described holding circuit is broken either by opening switch 68 or by failure of current supply.

The latch magnet 103, Figures 1, 2 and 3, is connected on one side via a lead 208 to the trunk conductor 192 and on the other to a conductor 218 connected to a third contact point 214 of the relay 130.

A second movable contact member or arm 213 of relay 130, adapted to engage point 214, is joined to arm 203 by a jumper 214A and thence via lead 204, switch 68 and branch 205 to the trunk conductor 189. It is evident from the above described connections that latch magnet 103 is energized whenever relay 130 is closed.

The push button switch 170 is adapted to connect the trunk conductor 189 via wires 209 and 201 to the relay 130. This switch thus parallels the thermal relay 131 and is operable independently of the latter to close the relay 130.

Motor circuits

55 A lead 210 forms a connection from the trunk conductor 192 to a third movable contact arm 211 on relay 130. The corresponding fixed contact 212 is connected via wire 212A to the lower motor 48, the other side of the latter being connected to trunk conductor 189. The switch 113, Figure 1, is connected in parallel across the contacts 211 and 212.

65 The upper or recording motor 139 has on one side a direct connecting lead 215 from the trunk conductor 192. The other lead 216 of motor 139 is connected to the central contact arm 75 of the double-throw switch 72, Figures 16, 17 and 22. The arm 75, as previously set forth, normally rests in engagement with the contact point 88 of switch 72. The second contact point 79 of switch 72 is electrically joined via a lead 217 to the conductor 218 connected at one end to the relay contact point 214 and at the other to an outer contact point 219 of one unit 166A of the four-pole triple throw manual switch 166, Figures 1

and 4. A jumper 220 connects the other outer point 221 of unit 166A with point 219. Central point 222 of switch 166A has no exterior connections. The contact arm 224 of unit 166A normally engages the idle central point 222.

A second unit 166D of the manual switch 166 has an arm 271 connected to the arm 224 through a lead 223 and to the trunk conductor 189 by a branch 225. The outer contact points 272 and 273 of switch unit 166D are bridged by a jumper 274, and the point 272 is connected via a wire 275 to the normally engaged contact point 80 of the cam switch 72. It will be noted from the foregoing description that the motor 139 is normally stopped, lacking a complete connection to the trunk conductor 189. Such a connection can be established by throwing the contact arm 75 into engagement with the contact point 81, a function carried out by the cam 57 during the automatic cycle as hereinafter set forth. However, with the switch 72 in normal position as shown, if the manual switch arms 224 and 271 are thrown either to the left or to the right into contact with their outer contact points, a circuit is also completed through the motor to conductor 225 and thence to trunk conductor 189, while at the same time a connection is established from conductor 189 to the conductor 218 independently of the relay 130. The purpose of this provision is to permit manual control of the motor 139 and amplifier 169 for play back and for direct recording, as explained more fully hereinafter in describing the general operation of the invention.

Automatic speech and recording circuits

It will be noted on Figure 22 that the manual switch 166 has additional units 166B and 166C having contact arms 249 and 237 respectively engaging central contact points 250 and 238 when in position for automatic operation, this position corresponding to the marking A on the dial 168, Figure 4.

Supply conductors 226 and 227 connected respectively to the conductor 218 and the trunk conductor 192 are provided to furnish primary current to the power transformer 228 of the amplifier 169. While any suitable type of amplifier may be used, for purposes of illustration a type is shown employing four amplifying tubes 229, 230, 231 and 232, and the usual rectifier tube 233. As the internal circuits and functions of such amplifiers are well known in the art, to avoid prolixity and unnecessary multiplication of numbers the present amplifier 169 need be described herein only in such details as affect its exterior connections.

The main input lead 234 of the amplifier is connected to the contact arm 77 of the double-throw cam-switch 74, Figure 16. In normal position the arm 77 is in engagement with stationary contact point 235, which is connected by a wire 236 with the movable contact arm 237 of triple-throw switch unit 166C, the latter being part of the manually operable switch 166, Figure 1. The arm 237 normally engages the central contact point 238 which is connected through adjustable resistor 239 to the lower reproducer or pickup 116, the other connection of 116 being the usual ground provision 240. Thus in normal automatic position the pickup 116 is connected to the amplifier input.

When the switch arm 77 is thrown, as previously set forth in connection with Figures 13 and 16, it engages its second contact point 241

which is coupled to the microphone 37 via the usual condenser 242, the tube 229 and an exterior lead 243. Thus throwing the arm 77 to the left connects the microphone to the amplifier input.

The movable arm 76 of the switch 73, Figure 16, is connected by a wire 244 with the secondary 245 of the output transformer 246. Arm 76 normally engages the contact point 247 which is connected through a wire 248 with the arm 249 of the three position manual switch unit 166B. The arm 249 is normally closed on its central contact point 250 which in turn is connected via an exterior lead 251 with the speaker 36. From the above description, it is evident that in normal position of the switches the speaker 36 is connected to the amplifier input lead 244.

The normally open signal switch 70, Figure 16, is connected between the wire 248 and the output conductors 244, for purposes hereinafter described.

When the switch arm 76 is thrown it engages its second contact point 252 which is connected through a lead 253 to the recorder head or cutter 146, which may thus be connected through to the output conductor 244.

Continuous recording and playback circuits

When the machine is set for automatic answering and recording, as noted throughout the foregoing description, the switch arms 224, 271, 249 and 237 of the three way manual switch 163 remain engaged with their middle contacts, this position being indicated at A on the dial 168, Figure 4. When it is desired to carry out direct recording independently of the automatic cycle, the switch arms 224, 271, 249 and 237 are thrown into engagement with their respective outer contact points 219, 272, 254 and 255, the recording position being indicated at R on the dial 164. This shift of arms 224 and 271 energizes the upper motor 139 as previously described. Contact point 254 is connected to the cutter 146 through a lead 256 and the conductor 253, so that in recording position as noted the cutter 146 is connected through to the output conductor 244.

The contact point 255 is connected by a wire 257 to the conductor 258 leading to the condenser 242. Thus shifting arm 237 into contact with point 255 again couples the microphone 37 to the input through the connections previously described.

When it is desired to play back a recording on the upper record, the arms 224, 271, 249 and 237 are manually thrown to the right into contact respectively with outer points 221, 273, 259 and 260, the pointer knob 167 indicating the position P on the dial 168, Figure 4. In this position, as previously set forth, the switch 166D throws the motor 139 into circuit between trunk conductors 189 and 192. The point 259, engaged by arm 249, is connected through a lead 261 and the wire 251 to the speaker 36, which by this means and the previously described connections is thrown into circuit with the output conductor 244. The point 260 is connected through a conductor 262 and the potentiometer 165 with the upper reproducer or pickup 164. Therefore, when the arm 237 is thrown into contact with the point 260, the pickup 164 is connected to the input conductor 234 through the switch 74 and previously described related elements.

Due to the fact that the amplifier supply conductor 226 is connected to the conductor 218

leading to the manual switch points 219 and 221, whenever the manual switch 166 is shifted to either play-back or straight recording positions the amplifier receives current at the same time that the upper motor 139 is started, but since the conductor 218 terminates at the normally disengaged contact member 214 of the relay 130, the lower motor 48 is not energized by the play-back or straight recording circuits. If desired, the small manual breaker switch 263 previously noted in the conductor 134A, may be opened to prevent any possibility of the starting circuit being completed by a telephone ring during these operations.

In order to assure prompt response from the amplifier 169 at all times, the filaments 264, 265, 266 and 267 of the amplifying tubes are kept heated independently by current supplied through conductors 268 and 269 from the low voltage secondary 195 of the transformer 194.

Operation

For automatic operation of the device, the telephone 98 is placed in front of the unit 30 as shown in Figures 1 and 4, the handset being placed on the supports 38 and 39 with the transmitter 41 and receiver 42 projecting into the cups 34 and 35 adjacent the speaker 36 and microphone 37. The arm 94 is swung downward until the weighted cross member 96 engages and depresses the telephone switch member 97, thus holding the telephone line disconnected. The screw 99 may be initially adjusted inwardly or outwardly according to the height of the particular telephone used, to assure that the member 96, in its normal lower position, holds the switch member 97 fully depressed. The cutter arm 142 is lowered by means of the handle 153 to place the cutting stylus 158 in engagement with the record blank 159. The master switch 171 is closed energizing the trunk conductors 189 and 192, and the manual switch knob 167 is placed at the central or "A" position, thus setting up the circuits previously described for automatic operation in switch 166.

Starting

When the bell 210 rings in the bell-box 179, Figure 6, the vibrations of the box 179 are transmitted through the cup 180 to the detector 178, causing the detector bar 184 to "dance" or "chatter" on the contacts 187 and 188. This action causes a succession of breaks in the normally closed circuit through the relay 129, allowing the latter's spring 199 to draw the armature 197 into engagement with the contact point 198. The action of the spring 199 is practically instantaneous, while the magnet of the relay 129 has sufficient lag that it is not able to re-open the contacts between all successive breaks of the circuit through the detector 178. As a result, the armature 197 and contact point 198 remains in substantially constant engagement throughout the duration of the ring. A circuit is thereby set up from the current supply trunk conductor 192, armature 197, contact 198, heating coil 134, branch 134A, closed switch 263, point 134B, arm 203, lead 204, switch 68 and lead 205 to the other current supply trunk conductor 189, causing the coil 134 to heat the bimetallic arm 131A.

As the arm 131A rises in temperature it bends toward the adjustable contact 133. However, for reasons hereinafter explained, the contact 133 is normally set sufficiently far from the bimetallic arm 131A that the latter does not receive suffi-

cient heat over the duration of single machine ring to enable 131A to bend entirely into contact with 133. During the interval after the first ring the coil 134 and arm 131A partially cool down, 5 the latter bending away from the point 133 a portion of the distance it has previously advanced. The second ring of the phone bell again energizes the coil in the manner described, and since some residual heat remains in the coil 134 and arm 131A, the latter bends still nearer the point 133. This process is repeated, the arm 131A advancing step by step until it has accumulated sufficient heat to bring it into contact with the point 133. Thereby the previously described 10 circuit is closed from trunk conductor 189, bimetallic arm 131A, contact point 133, leads 200 and 201, the relay 130, and the branch 202 to the trunk conductor 192. The relay 130 being energized, closes its contacts to start the cyclic 15 operation of the machine.

It is evident from the foregoing that the detector 178 operates purely by direct mechanical vibration, requiring no electrical, inductive or acoustic coupling or tuning with the telephone 20 circuit or bell. The contact 133, being adjustable as shown in Figure 9, may be set to require any desired number of successive rings or the equivalent in a long continuous ring before the starting contact is made. This coding or adjustable time delay provision prevents the starting circuit from being closed by accidental jarring of the bell box, for example by slamming doors or other extraneous vibrations, which accidental starting may occur with any type of apparatus operable at the first impulse, while at the same time this simple and cheap apparatus avoids the use of more expensive and complicated-step-by-step code relays and the like. When the relay 130 closes as noted above it also breaks the heater coil circuit through 134 at the contact point 134B, 25 on this relay, preventing any possible additional heating of coil 134 during the cycle.

The relay 130 having been energized by the starting circuit closes its three contacts to energize the amplifier 169, the latch magnet 103 and the motor 48 through the previously described 30 connections, thereby starting the cycle of operations. The successive functions of the cycle may best be followed by reference to the polar timing 35 diagram Figure 21, in which the clockwise direction from the point indicated "start" indicates the relationship of these functions.

Answering

As the motor 48 starts, it rotates the lower 55 turntable 46 and through the shaft 45 and worm gearing 53 and 52, the cam-shaft 51 and its cams 54, 55, 56 and 57 are also rotated. The initial movement of the cam 56, Figure 14, rocks the 60 arm 88 outward, thereby also rocking the shaft 84 and its arm 91, Figure 1, and thrusting the finger 108 forward. The magnet 103 being energized, holds the detent 107 in latching position and the forwardly moving finger 108 in engagement with the detent rocks the channel lever forward, thereby rocking the exterior arm 94 upward. This movement raises the weighted member 96 from the phone switch member 97, 65 allowing the latter to rise and complete the telephone circuit. During the rocking of the shaft 84, the extension 112 closes the switch 113, Figure 1.

At the same time that the above actions are taking place, the pin 124 of lever 120, Figures 70 10, 11 and 15, rides down the slope of cam 57

to the reduced portion of the latter, thus causing the lever 120 to lower the pickup arm 114 until the needle 117 of pickup 116 engages the record 47 at the outer edge of one of the zones on the latter, for example zone 127, Figure 8. The zone 127 carries a recording of any desired answering speech, for example—"Mr. Blank is not at home, but if you wish to leave a message the automatic recorder will record it for him. When you hear the signal, speak directly into the telephone for not over thirty-five seconds." The pickup 116 being connected to the amplifier input as previously described and the speaker 36 similarly being connected to the output, the speech recording is picked up, amplified, and spoken by the speaker 36 into the phone transmitter 41 in the cup 34. The duration of this answering period is indicated by the segment labelled "answering," Figure 21. At the end of this period the lift lever 120 is again rocked upward, raising the pickup arm 114 away from the record and allowing the leg 119 to slide down the notch 123, thereby returning the pickup 116 to initial position ready for its next repetition of the answering speech.

Message recording

During the foregoing rise of the lower pickup arm, the end 65A of the enlarged portion 65 of cam 55, Figure 13, releases the gang-switch lever 81, allowing the spring 82 to shift the gang-switch arms 75, 76 and 77 of switch 71 into contact with their second contacts 79, 252 and 241, Figure 22. By this operation, as previously described in detail in connection with Figure 22, the upper motor 139 is started, the pickup 116 and speaker 36 are disconnected, the microphone 37 is coupled to the amplifier input, and the cutter 146 is connected to the output.

Shortly after the above shift has occurred, the pin 69, Figures 13 and 16, momentarily closes the signal switch 10. By reference to Figure 22 it will be seen that this closure momentarily reconnects the speaker 36 to the output transformer 246. Thus the speaker 36 and microphone 243 are both connected to the amplifier at the same time, and due to their relative nearness in the casing 31 and the clearance past the telephone receiver and transmitter in cups 35 and 34, an acoustic coupling is set up between the microphone and speaker, causing the latter to emit a tone which is transmitted out through the phone. This momentary tone serves as a signal to the person calling to begin delivering his message.

As the caller speaks, his message is delivered by the telephone receiver 42 to the microphone 37, whence it is carried to the amplifier, amplified and recorded by the cutter stylus 158 on the record blank 159. At the end of the recording period the breaker switch 68 is momentarily opened by the pin 67 on cam 55, Figures 13 and 18. This breaks the holding circuit through the relay 130, allowing the latter to open and de-energize the amplifier 169, motor 139, and latch magnet 103.

The magnet 103 releases the armature 104, Figure 3, allowing the weight of the cross member 96 and arm 94 to swing the lever 92 inward, the detent 107 over-riding the finger 108. The weighted member 96 in dropping, depresses the switch member 97 to disconnect the telephone circuit, terminating the call.

The motor 48 continues to run, the roller 89, Figure 13, rolling down into the notch 83 in cam 75

56 under the urge of the torsion spring 80 which rocks the rocker shaft 84 with the lever 91 and extension 112 counterclockwise. Thereby the finger 108 is retracted behind the detent 107, the latter meanwhile having been returned to initial latching position as shown in Figure 1 by the light spring 104A. The extension 112 also allows the switch 113 to open, de-energizing the motor 48. The motor 48, turn-table 46 and cam-shaft 10 51 come to a stop with a small amount of "coast" due to momentum, this period being represented in Figure 21 by the segment labelled "Stopping." During the coast the cam 55, Figure 13, throws the lever 81 and connected gang-switch 71 back to initial position against the urge of torsion spring 82, the resistance furnished by this spring acting, through the lever 81 against the cam slope, as a brake to limit the coasting. The entire control mechanism having returned to stop in initial position, the device is ready for the next call, whereupon the entire cycle is repeated in the same manner described.

The record blank 159 comprises sufficient surface for a number of successive message recordings, the exact number being determined by the size of record cuts per inch, recording R. P. M. and duration of the recording period, these factors being proportioned to give the maximum number of call recordings normally required during average periods in which the telephone is unattended. During such a period the cutter stylus 158 remains engaged with the record blank 159 and the knife edge 150 remains engaged with the feed screw 141, so no attendance is necessary between successive recordings of a series of messages.

If at any time the number of successive incoming calls exceeds the capacity of the record blank 159, the feeding arm 149 at its inner limit of travel engages and opens the limit switch 173, Figures 1 and 3, breaking the main circuit and holding the machine out of operation until a new record blank surface is provided.

Current failure release

45 In case of current failure during a call, for example if a fuse blows somewhere in the supply line, of course the entire mechanism stops and remains stopped until current is restored. During such a period, which may be of considerable length, it is undesirable that the telephone should remain "open" that is, connected. In the present invention the provision of the latch 101 eliminates this possibility, since current failure de-energizes the magnet 103 to release the finger 108 as shown 50 in Figure 3, allowing the weighted cross member 96 to drop on the switch member 97 and thereby disconnect the telephone. When current is restored the arm 94 and member 96 cannot be lifted by the mechanism until the finger 108 has 55 been retracted behind the detent 107, and this can only be brought about by completing the cycle of the cam 56.

In the above case of current failure during the cycle, lack of current also will have allowed the relay 130 to drop out, and upon restoration of current the relay normally remains open so that no current is restored through its contacts to the motor 48, latch magnet 103, motor 139 or amplifier 169. However, the motor 48 is individually supplied with restored current through the switch 113 which is held closed throughout the cycle by lever extension 112, Figure 1. The motor 48 therefore starts and drives the control mechanism to the completion of the interrupted cycle,

thus restoring the device to normal condition ready to answer the next incoming call. To summarize the foregoing, failure of current simply disables the device and if the failure occurs during a cycle, terminates the phone call. Upon restoration of current the device automatically restores itself to normal start position without disturbing the telephone circuit. It is thus impossible for the machine to start answering a call on partial cycle. Even in the extremely coincidental case of an incoming call ring occurring immediately after current restoration, the telephone circuit is not completed until the device has reached normal start position, whereupon, if the call has persisted it is answered in the normal manner as described.

When the machine is not in use, for example when a person is present to answer the phone directly, the handset 40 may be removed from the cups 34 and 35 and placed on its switch member 97 in the usual position, the arm 94 being folded upward into the position shown in Figure 4. In this position it will be noted that the arm 94 and cross member 96 are so disposed as to interfere with placing of the handset in the cups 34 and 35. This arrangement prevents a user from forgetting to lower the member 96 on the phone switch member when setting the device for automatic operation.

Recording answering speeches

As previously stated, any desired answering speech recording of proper length may be carried by the lower record 47; such a speech may be recorded by the user as follows:

The telephone handset is removed and the arm 94 swung up as explained above. A record blank is placed on the upper turn-table 138 and the cutter arm 142 is set in any desired notch in the shoe 152, such as notch 155, Figures 4 and 16. The shoe 152 is swung forward, lowering the cutter arm to bring the stylus 158 on the record blank at the outer edge of the desired recording zone 127 and placing the knife edge 150 in mesh with the feed screw 141.

The user next presses the push-button switch 170, energizing the relay 130 through the wire 209, Figure 22. The relay 130 closes and starts the machine through a cycle. The user waits until he hears the signal tone at the point shown in Figure 21, that is when the motor 139 has started and the device is conditioned for recording. The user then speaks the desired answering speech into the cup 35. The microphone 37 receives the speech in the usual manner and relays it through the amplifier 169 to the cutter 146 which makes a recording thereof on the record blank.

The spiral lobe 58 of the indicator cam 54 is so located and proportioned that through the previously described mechanical connections it moves the exterior indicator or timer pointer 64 upward along the scale 65, Figures 4 and 5, starting the pointer upward as the signal sounds and completing the movement at the end of a period of time equal to the desired length of the "answering" period. For example, if the normal answering period set by the control apparatus is twenty seconds, the cam 54 is proportioned to raise the pointer 64 uniformly along the entire scale 65 in twenty seconds, and the scale is calibrated from zero to twenty as shown in Figures 4 and 5. By watching the upward progress of the pointer, the person recording the "answering" speech is enabled to time his message accurately, so as to

bring its recording properly in the required zone on the record blank. Having completed his speech recording the operator raises the cutter arm 146, waits until the automatic cycle is completed, then transfers the newly made answering record to the lower turn-table 48 where it becomes the record 47. The lower reproducer arm 114 is set with its leg 119 in the proper notch 123 to lower the pickup needle 117 into the recorded zone 127, a new blank 159 is placed on the upper table, and the device is again ready for use as previously described, each following call being answered by the newly recorded speech.

As many answering speeches may be made on one record as there are notches in the lift lever 120, Figures 10 and 11, and any one of the speeches may be utilized for answering a particular series of calls by setting the leg 119 in the proper notch in lever 120.

It is obvious that by using slow rotative record speeds and a relatively large number of lines per inch, a larger number of answering speeches and incoming calls may be recorded per record, the proportions, number of notches 123, etc., of the present example being given only for purposes of illustration. It will also be noted that the machine may be constructed for any desired lengths and proportions of the answering and recording periods, these functions being dependent only on the rotative speed and proportioning of the control cams.

When a speech is being made as described above, the lower pickup 116 may be allowed to operate on a previously made record or may be swung clear of its turn-table 48. A door 276, Figure 5, is provided in the side of the casing 31 to allow access to the lower turn-table and related parts.

Playback

When a series of recordings of telephone messages has been automatically made on an upper record blank 159, and the user wishes to reproduce or play back the recordings, the procedure is as follows:

The cutter arm 142 is raised, the shoe 152 springing back to hold the recording mechanism disengaged as previously explained. The manual switch knob 167 is turned to "P" position, throwing the various arms of switch 166 to their right-hand contact positions in Figure 22. This shift operates through the various connections previously traced and explained in detail to energize the motor 139 and amplifier 169, connect the amplifier output to the speaker 38, and connect the upper pickup 164 to the input. The operator then places the pickup 164 with its needle in engagement with the recordings on blank 159 in the usual manner, the messages being played or spoken by the speaker 38 through the cup 34. If desired the handset 40 may be removed during playback but this is not usually necessary, as the clearance between the cup 34 and transmitter 41 is sufficient for emission of the sound. The volume of reproduction may be controlled by means of the potentiometer 165.

To prevent any possibility of the automatic starting circuit being closed by a phone ring during a playback, the manual switch 263 may be opened to disable the circuit of heater 134.

Straight recording

When it is desired to perform straight recording on the blank 159 for any purpose such as dictation, leaving office instructions, or the like, the handset 40 is removed, the manual switch

knob 167 is turned to "R" position, Figure 4, and the cutter stylus 158 is lowered into engagement with the record blank 159 by means of lever 153. The shift of knob 167 throws the arms of switch 166 to their left hand contact positions, Figure 22, again energizing the motor 139 and amplifier 169, connecting the cutter 146 to the amplifier output and coupling the microphone 37 to the input, all as previously traced and explained in detail. The speech or other sound to be recorded is directed into the cup 35 where it is received by the microphone 37, transferred through the amplifier to the cutter 146, and recorded on the blank 159. The recording may continue throughout a part of or the entire surface of the blank 159, since the control is entirely manual. As in the case of playback, the switch 263 may be opened to disable the automatic starting circuit. Records containing telephone messages, etc., may be played back as often as desired, and may then be filed or thrown away. Since high fidelity or great durability are not necessary, any suitable cheap type of record may be used.

From the description of the apparatus and operation, it is evident that the invention provides an effective means to accomplish the purposes set forth, comprising a device which is simply and readily operable by anyone familiar with telephone and phonograph operation. Due to its relative simplicity and lack of high precision parts it may be easily and cheaply manufactured, while the lack of any inductive, magnetic, electrical or acoustic detector, together with the automatic release latch mechanism, preclude the possibility of any accidental disturbance of the normal telephone circuits.

While the invention has been described in preferred form it is not limited to the exact structures illustrated, as various modifications may be made without departing from the scope of the appended claims.

What is claimed is:

1. In a device of the character described, in combination, means for translating an incoming telephone signal including a relay, a motor circuit controlled by said relay, a motor in said circuit, switch mechanism operated by said motor, a record, a phonograph reproducer cyclically controlled by said motor whereby said reproducer is placed upon and removed from said record, a speaker for audibly reproducing the sounds recorded on said record connected to said reproducer, means driven by said motor for moving said record, recording means cyclically controlled by said switch mechanism whereby said recording means when moved over a second record will record thereon, a second record, and a second motor for moving said second record and recording means and cyclically controlled by the operation of said first motor.

2. In a device of the character described, a starting circuit including a relay, a telephone switch actuating member, means for actuating said member controlled by said relay, a motor controlled by said relay, a record moved by said motor, a reproducer, means actuated by said motor for causing said reproducer to engage and disengage said record, an amplifier, means including a circuit and a source of energy for energizing said amplifier controlled by said relay, recording means, and means actuated by said motor for alternately placing said reproducer and said recording means in circuit with said amplifier.

3. In a device of the character described, a starting circuit including a relay, a motor circuit controlled by said relay, a motor in said last circuit, a switch cyclically operated by said motor, a record, a reproducer cyclically controlled by said motor whereby said reproducer is placed upon and removed from said record, means driven by said motor for moving said record, recording means controlled by said switch, a second record, means controlled by said switch for relatively moving said second record and recording means, a speaker controlled by said switch and cyclically connected to said reproducer, a cabinet in and upon which all of the foregoing parts are mounted in cooperative relationship to form a unit device, said cabinet having means therein to position the transmitter of a telephone instrument adjacent said speaker, whereby the telephone transmitter and said speaker are acoustically coupled.

4. In a device of the character described, a starting circuit including a relay, a motor circuit controlled by said relay, a motor in said last circuit, switching means cyclically operated by said motor, a record, a reproducer, means cyclically operated by said motor and connected to said reproducer to cause same to engage and disengage said record, means driven by said motor for moving said record, a speaker controlled by said switching mechanism and selectively connected to said reproducer, recording means controlled by said switching means, a record blank, means controlled by said switch for relatively moving said blank and said recording means to record on said blank, a microphone controlled by said switching mechanism and selectively connected to said recording means, and a cabinet in and upon which all of the foregoing instrumentalities are mounted in cooperative relationship to form a unit device, said cabinet having means therein to acoustically couple the transmitter and receiver of a telephone instrument respectively to said speaker and microphone.

5. In a device of the character described, a starting circuit including a relay, a motor circuit controlled by said relay, a motor in said last circuit, switching means cyclically operated by said motor, a record, a reproducer, means cyclically operated by said motor and connected to said reproducer to cause same to engage and disengage said record, means driven by said motor for moving said record, a speaker controlled by said switching mechanism and selectively connected to said reproducer, recording means controlled by said switching means, a record blank, means controlled by said switch for relatively moving said blank and said recording means to record on said blank, a microphone controlled by said switching mechanism and selectively connected to said recording means, a second reproducer adapted to engage said record blank, manual switching means to connect said second reproducer to said speaker and for controlling the movement of said record blank, and a cabinet in and upon which all of the foregoing instrumentalities are mounted in cooperative relationship to form a unit device, said cabinet having means therein to acoustically couple the transmitter and receiver of a telephone instrument respectively to said speaker and microphone.

6. In a device of the character described, a starting circuit including a relay, a motor circuit controlled by said relay, a motor in said last

circuit, switching means cyclically operated by said motor, a record, a reproducer, means cyclically operated by said motor and connected to said reproducer to cause same to engage and disengage said record, means driven by said motor for moving said record, a speaker controlled by said switching mechanism and selectively connected to said reproducer, recording means controlled by said switching means, a record blank, means controlled by said switch for relatively moving said blank and said recording means to record on said blank, a microphone controlled by said switching mechanism and selectively connected to said recording means, manual switching means for connecting said recording means to said microphone and for controlling the movement of said record blank, and a cabinet in and upon which all of the foregoing instrumentalities are mounted in cooperative relationship to form a unit device, said cabinet having means therein to acoustically couple the transmitter and receiver of a telephone instrument respectively to said speaker and microphone.

7. In a device of the character described, a starting circuit including a relay, a motor circuit controlled by said relay, a motor in said last circuit, switching means cyclically operated by said motor, a record, a reproducer, means cyclically operated by said motor and connected to said reproducer to cause same to engage and disengage said record, means driven by said motor for moving said record, a speaker controlled by said switching mechanism and selectively connected to said reproducer, recording means, a record blank, means controlled by said switch for relatively moving said blank and said recording means to record on said blank, a microphone controlled by said switching mechanism and selectively connected to said recording means, a second reproducer adapted to engage said record blank, manual switching means having a position in which it connects said second reproducer to said speaker and for controlling the movement of said record blank and another position in which it connects said recording means to said microphone and for controlling the movement of said record blank, and a cabinet in and upon which all of the foregoing instrumentalities are mounted in co-operative relationship to form a unit device, said cabinet having means therein to acoustically couple the transmitter and receiver of a telephone instrument respectively to said speaker and microphone.

8. In a device of the character described, a starting circuit including a source of current and instrumentalities for controlling a motor, a motor circuit including a motor controlled by said first circuit, a reproducing phonograph including a movable sound record, a recording phonograph including a movable sound record blank, a speaker, a microphone, and switching means operated by said motor for cyclically connecting said reproducing phonograph to said speaker, disconnecting the same and connecting said recording phonograph to said microphone, disconnecting the same and disconnecting said motor from its circuit at a predetermined point in the cycle.

9. In a device of the character described, a starting circuit including a source of current and instrumentalities for controlling a motor, a motor circuit including a motor controlled by said first circuit, a reproducing phonograph in-

cluding a movable sound record, a recording phonograph including a movable sound record blank, a speaker, a microphone, switching means operable by said motor to cyclically connect said speaker and microphone respectively to said reproducing and recording phonographs, and second switching means cyclically operated by said motor whereby upon the initial movement of same a running circuit is established independently of said starting circuit to maintain the motor in continuous operation throughout said cycle, said second switching means further acting to disconnect said motor from its circuit at a predetermined point in the cycle.

15. In a device of the character described, a starting circuit including a source of current and instrumentalities for controlling a motor, a motor circuit including a motor controlled by said first circuit, a reproducing phonograph including

20 first circuit, a reproducing phonograph including a movable sound record, a recording phonograph including a movable sound record blank, a speaker, a microphone, an amplifier, and switching means operated by said motor for cyclically connecting said reproducing phonograph to said amplifier and the latter to said speaker, disconnecting the same, connecting said recording phonograph to said amplifier and the latter to said microphone, disconnecting the same, and finally disconnecting said motor from its circuit
25 at a predetermined point in the cycle.

35 at a predetermined point in the cycle.

36 11. In a device of the class described, a member for actuating the switching mechanism of a telephone instrument, said member in its normal position tending to hold said switching mechanism in open circuit position, said member when actuated being adapted to permit said switching mechanism to move to closed circuit position, actuating means operable by electric current for moving said member to permit said switching mechanism to move to closed circuit position, and means operable upon the failure of said current to release said member from said actuating means to permit said member to return to normal and thereby restore said switching mechanism to open circuit position.

40

45

12. A device as claimed in claim 11 wherein the actuating means for moving said member includes a motor driven cam.

13. In a device of the character described, a
50 member for actuating the switching mechanism
of a telephone instrument, said member in its
normal position tending to hold said switching
mechanism in open circuit position by gravity,
said member when actuated against gravity be-
ing adapted to permit said switching mechanism
55 to move to closed circuit position, actuating
means operable by electric current for moving
said member to permit said switching mecha-
nism to move to closed circuit position, and
60 means operable upon the failure of said current
to release said member from said actuating
means to permit said member to return to nor-
mal by the force of gravity and thereby restore
65 said switching mechanism to open circuit posi-
tion.

14. In a device of the character described, a member for actuating the switching mechanism of a telephone instrument, said member in its normal position tending to hold said switching mechanism in open circuit position, said member when actuated being adapted to permit said switching mechanism to move to closed circuit position, actuating means operable by electric current for moving said member to permit said switching mechanism to move to closed circuit

position, and means including a magnetic release mechanism operable upon failure of said electric current to release said member from said actuating means.

15. In a device of the class described, means for actuating the switch mechanism of a telephone instrument including a support, a pivoted arm on said support, means for adjusting the position of the outer free end of said arm, a lever on said support adapted to engage and move said arm, means for moving said lever including a cyclically actuated member, and electrically actuated means for releasing said last member from said lever upon failure of the current operating said electrically actuated means.

16. In a device of the character described, in combination, a casing, a vertically movable arm pivoted in said casing and extending outwardly therefrom, a weighted member on said arm adapted to engage the switch member of a telephone, a lever pivoted in said casing and operatively engaging said arm, a latch frame on said lever, a detent movably attached to said frame, a movable finger in said casing adapted to engage said detent, an electro-magnet on said frame and adapted to hold said detent in engaged position, electrically operable means for moving said finger and engaged detent whereby said lever may raise said arm and weighted member, and a common source of current connected to said moving means and said electro-magnet.

17. The combination claimed in claim 16 wherein said electrically operable means includes a motor-driven cam adapted to advance said finger to a forward position and retain the same in said position throughout a predetermined time cycle.

18. The combination claimed in claim 16 including a pair of cups mounted in said casing and adapted to receive the transmitter and receiver of said telephone, and wherein said arm is adapted to be manually swung to an upper position away from said switch member, said weighted member partly overlying said cups when in said upper position.

19. In a device of the character described, a cabinet forming a support, a speaker and a microphone carried on said support, means overlying said speaker and microphone and adapted to respectively acoustically couple a telephone transmitter and receiver thereto, said means including positioning members adapted to loosely receive at least a portion of said telephone transmitter and receiver so as to support same in operative relationship to said speaker and microphone, means within said cabinet for operating said speaker and microphone including an electric motor and an operating circuit therefor, means for controlling the operation of said motor including circuit controlling means spaced apart from said cabinet and connected to the motor operating circuit therein, and means operatively connected to said motor and extending from said cabinet and adapted to actuate the switching mechanism of a telephone instrument including an arm pivoted to swing to non-operating position to overlie said positioning members to prevent placing a telephone transmitter and receiver therein when said arm is in said non-operating position.

20. In a device of the character described, mechanism for actuating the switching mechanism of a telephone instrument including a pivoted arm, means operable by a telephone signal

to move said arm to actuate the telephone switching mechanism, said arm being manually adjustable about its pivot to another position wherein it is disassociated from said means.

5 21. In a device of the character described, sound recording and reproducing mechanism including a speaker and microphone, a cabinet enclosing the same, said cabinet having apertures in a wall thereof, said speaker and microphone being respectively located below said apertures and within said cabinet, said apertures being spaced to receive at least a portion of the transmitter and receiver of a telephone instrument while leaving clearances through said apertures 10 and means for supporting said telephone transmitter and receiver on said cabinet in acoustically coupled relationship to said speaker and microphone.

22. In a device of the character described, sound recording and reproducing mechanism including a speaker and microphone, a cabinet having apertures therein, members forming separate chambers within said cabinet in open communication with said apertures, said speaker and microphone being positioned in said separate chambers, said apertures being adapted to receive at least a portion of the receiver and transmitter of a telephone instrument to acoustically couple said transmitter and receiver to said speaker and microphone respectively, while providing clearance through said apertures, each of said members having side walls forming acoustic insulation laterally between said chambers.

25 30 35 40 45 50 55 60 65 70 75 23. In a device of the character described, a support having apertures therein, members forming chambers about said apertures, a speaker in one of said chambers, a microphone in another of said chambers, a telephone hand set having a transmitter and receiver located respectively in said apertures whereby said transmitter and receiver are respectively acoustically coupled to said speaker and microphone while said hand set is positioned on said support, said apertures being substantially greater than the diameters of said transmitter and receiver, and recording and reproducing means connected to said speaker and microphone.

24. In a device of the class described, a hollow body having a transmitter opening and a receiver opening spaced apart by a distance equal to the spacing between the transmitter and receiver of a telephone instrument, said openings leading from acoustic chambers within said body, rings around said chambers substantially larger than the diameter of the transmitter and receiver bodies of a telephone instrument and adapted to loosely receive the transmitter and receiver, respectively, of a telephone instrument, means located between said rings to support a telephone instrument in fixed relation to said rings, and a speaker and a microphone positioned within said body in communication with the said acoustic chambers leading to the transmitter and receiver respectively.

25. In a device of the character described, a support having apertures therein, members forming chambers behind said apertures, a speaker in one chamber, a microphone in another chamber, a telephone transmitter positioned by said support and projecting into the aperture therein communicating with the chamber in which said speaker is located, a telephone receiver therein connecting with the chamber in which said microphone is located, said telephone transmitt-

ter and receiver being parts of a subscriber's telephone instrument having switching mechanism for connecting same to a telephone line, means comprising a movable arm projecting from said support and adapted to actuate said telephone switching mechanism, and means for operating said arm, speaker and microphone.

26. The combination with a telephone instrument comprising an audible signalling device, a transmitter, a receiver and switching mechanism, of a recording device including a signal detector adapted to be actuated by vibrations of said audible signal device, a circuit including said detector and a source of current and a control relay, means controlled by said relay for operating the switching mechanism of the telephone instrument, a sound recorder and reproducer, an amplifier, a microphone adjacent the telephone receiver and adapted to pick up sounds emanating therefrom, a speaker adjacent the telephone transmitter and adapted to deliver sound vibrations thereto, a motor, means controlled by said relay for completing a circuit from said source of current through said motor including switch mechanism and circuits therefor to sequentially connect first, said reproducer to the input circuit of said amplifier and said speaker to the output circuit thereof whereby a recorded message may be transmitted over the telephone, secondly, to disconnect said reproducer and speaker and connect said microphone to the input circuit of said amplifier and said recorder to the output circuit thereof, whereby an incoming message over said telephone may be recorded.

27. In a device of the character described, a cabinet having a base, top and side walls, phonograph mechanism mounted on said base within said cabinet and adjacent the front wall thereof, said cabinet having a door to permit access to said phonograph mechanism to permit records to be placed thereon and removed therefrom, telephone switch operating mechanism extending outwardly from a wall of the cabinet, apertures in said wall of the cabinet adapted to receive a telephone transmitter and receiver, a speaker adjacent one of said apertures, a microphone adjacent the other of said apertures, a second phonograph mechanism mounted on said top of said cabinet including a record table overlying said top, a cover for the top of said cabinet enclosing said record table, and means within said cabinet for operating said phonograph mechanisms, switch operating mechanism, speaker and microphone.

28. In a device of the character described, a phonograph including a turntable and a swinging arm adapted to overlie the same, translating means carried by said arm, means for raising and lowering said arm to cause said translating means to engage and disengage a record carried on said turntable, a second phonograph including a turntable and two swinging arms adapted to overlie the same, translating means carried by said arms, means for causing one of said arms to traverse a record as it is revolved by said last turntable, said arm being manually disconnectable from said means whereby it may be moved outside the periphery of its associated record, the other of said two arms adapted to be manually positioned to engage said record and traverse the same, means for rotating said turntables, means controlled by the operation of one of said phonographs for starting and stopping the other phonograph, a speaker and microphone selectively con-

nectable to said translating means, and means to momentarily connect said speaker and microphone at the same time to said translating means.

29. In a device of the character described, a phonograph including a reproducer and a record support having a recorded record thereon, a second phonograph including a record support having a record blank thereon, recording means adapted to record on said blank and movable to a non-operative position relative thereto, a reproducer adapted to engage said record blank and reproduce any recording thereon and movable to a non-operative position relative thereto, a speaker, a microphone, an amplifier, switch means for selectively connecting either of said reproducers to said speaker via said amplifier, switch means for connecting said recording means to said microphone via said amplifier, means for relatively moving said records, recording means and reproducer, a source of current for operating said driving means and said amplifier, and means connected to and operable with either of said switch means to connect said driving means and said amplifier to said source of current.

30. In a device of the character described, a phonograph including a reproducer and a record support having a recorded record thereon, a second phonograph including a record support having a record blank thereon, recording means adapted to record on said blank and movable to a non-operative position relative thereto, a reproducer adapted to engage said record blank and reproduce any recording thereon and movable to a non-operative position relative thereto, a speaker, a microphone, an amplifier, switch means for selectively connecting either of said reproducers via said amplifier to said speaker, switch means for connecting said recording means via said amplifier to said microphone, means for relatively moving said records, recording means and reproducer, a source of current for operating said driving means and amplifier, and starting means including a circuit having a control relay therein operated by said source of current and controlling the application thereof to said amplifier and driving means.

31. The combination as claimed in claim 30 wherein the starting means includes a time delay device operable to delay actuation of said control relay.

32. The combination as claimed in claim 30 wherein the starting means includes a thermal time delay device operable to delay actuation of said control relay, said relay having a normally closed contact in circuit with said thermal device whereby actuation of said relay disables said thermal device.

33. The combination as claimed in claim 30 wherein the starting means includes a detector, an impulse relay controllable by said detector to transmit pulses of current via a time delay device to said control relay, a locking contact on said control relay to close a holding circuit therethrough to lock the same in closed contact position, and a cyclically operated switch adapted to open the holding circuit through said relay after a pre-determined period.

34. The combination as claimed in claim 30 wherein the starting means includes a manually operable switch adapted to complete a holding circuit through said control relay to cause same to lock in closed contact position, and a cyclically operated switch adapted to open the holding circuit through said relay after a predetermined period.

35. In a device of the character described, a member adapted to be connected to the switching mechanism of a telephone instrument, electricaly operated means for actuating said member to open and close the switch contacts of said mechanism, and a no-current release device for releasing said member from said electrically operated means to permit said member to restore the telephone switching mechanism to open circuit position in the event of failure of the current supply to said means.

36. In a device of the character described, operating means for actuating the switching mechanism of a telephone instrument, a phonograph mechanism including a record blank supported thereon, a recorder movable over said blank, a microphone, switch mechanism adapted to connect and disconnect said recorder to and from said microphone, means for driving said phonograph mechanism, a circuit including a source of current for operating said operating means, recorder, microphone and driving means, and a limit switch actuated by the movement of said recorder when the recording on said record has reached a pre-determined point to open the circuit to said source of current, thereby stopping the operation of all said devices.

37. The combination as claimed in claim 36 wherein a manually controlled master switch is serially included in circuit with said limit switch, and including a tell-tale light controlled by the operation of said switches.

38. The combination with a subscriber's telephone set having a telephone ringer, of means to cause a recorded message to be reproduced and delivered to the calling subscriber and an incoming message from said calling subscriber to be recorded, said means including separate record members, means for moving said records, electrical means including a vibratory detector actuated by the mechanical vibrations of the telephone set independently of the sound produced by the telephone ringer to automatically control the operation of said record moving means, and manually operable means operable independently of said detector to control the operation of said record moving means.

39. In an apparatus of the class described adapted to be associated with a subscriber's telephone set and having means for recording an incoming message on a record and reproducing an outgoing message from another record, movable records, record moving means, controlling means operated by a source of current separate from that in said-subscriber's telephone to govern the actuation of said record moving means, said controlling means including a member movable to a lower and an upper position to mechanically cause the switch of said telephone to occupy upper and lower positions corresponding to the upper and lower positions of said member thereby controlling the circuits of said telephone set.

40. In an apparatus for use with telephones, the combination of a phonograph, electro-mechanical means for starting the operation of said phonograph, mechanical means including a switch for continuing the operation of said phonograph over a predetermined period, and means for effecting the release of said electro-mechanical means to stop the operation of said phonograph at the end of said period.

41. In a device as claimed in claim 40, a time delay device adapted to control the starting operation of said electro-mechanical means.

42. In a device adapted to be used with a subscriber's telephone set having a switch, means for recording an incoming message and reproducing an outgoing message, a movable record, means to move said record, controlling means, means actuated by an incoming signal to said telephone set to actuate said controlling means, an arm member between the switch of the telephone set and said controlling means and movable by said controlling means to mechanically permit said switch to operate to close a circuit through said telephone set by the release of said arm therefrom, said arm being adjustable to permit the use of different telephone sets therewith.

43. In an apparatus of the character described, a record blank, means traversing said blank for recording a message thereon, a motor for moving said means, a device responsive to mechanical vibrations for closing a circuit through said motor to start the recording, and stop means including a switch operable by said traversing means for opening said circuit through said motor.

44. In a device cooperative with a telephone, in combination, a phonograph adapted to reproduce a previously recorded answering speech, means to direct said speech into the transmitter of said telephone, a recording phonograph adapted to record a message, means to transmit messages incoming from the receiver of said telephone to said recording phonograph, means to release the circuit switch of said telephone, electrically operable means to control the operation of said release means and said phonographs in a pre-determined cycle, a source of current for said control means, a relay adapted upon energization to connect said control means to said source and thereby start said cycle, means to energize said relay including a normally open thermostatic switch, said switch being adapted to close upon accumulation of a pre-determined amount of heat therein, an electric heating coil in heat-exchange relationship with said switch, said telephone having vibratory signalling means, and means including a detector responsive to direct mechanical vibrations of said signalling means to direct successive increments of current through said heater coil to incrementally accumulate said pre-determined heat quantity in said thermostatic switch.

45. In a device of the character described, in combination, a casing, a recording phonograph in said casing having a recording stylus and adapted to carry a record blank, means to actuate said recording phonograph, manual means

55 to guide said stylus into engagement with said record at the entering limit of a predetermined zone thereon whereby said phonograph may record sound effects within said zone, a reproducing phonograph in said casing adapted to receive said

60 blank and having a pickup needle, means to drive said reproducing phonograph, timing means operable by said driving means, a cam on said timing means adapted to guide said pickup needle into engagement with the entering limit of said

65 zone whereby said reproducing phonograph may reproduce said recording in said zone, means on said cam to disengage said needle from said record at the termination of said reproduction, second cam means on said timing means to start said

70 actuating means whereby said recording phonograph may be actuated throughout a recording period in cyclic succession to said reproduction, a scale on said casing, an indicator cooperative with said scale, and means on said timing means to move said indicator throughout the length of said

scale in a time interval substantially equal to the time length of said reproduction, said indicated time interval being comprised in said recording period.

46. In combination, a support, reproducer mechanism mounted upon said support to traverse a record and including an arm supporting said reproducer, said arm having an initial starting position, a record, driving means to relatively move said record and reproducer, means carried by said support to cause said reproducer to engage and disengage said record including a member adapted to lift and lower said reproducer arm relative to said record, said member having means therein to return said reproducer arm to starting position after disengaging said reproducer from said record.

47. In combination, a support, reproducer mechanism mounted upon said support including a horizontal arm pivoted at one end and movable radially and vertically, a record, driving means for relatively moving said record and arm whereby said reproducer may traverse said record, means carried by said support including a member in engagement with said horizontal arm to lift and lower the same, means operated by said driving means and engaging said member to lift and lower the same, said means being controlled by said driving means whereby said reproducer is lowered to engage said record at a predetermined point and lifted from said record at another predetermined point, during the operation of said driving means.

48. In a device of the character described, in

combination, a shaft, a turn-table on said shaft adapted to hold a record, means to rotate said turn-table and shaft, a reproducer adjacent said turn-table and adapted to engage said record, said record having a sound recording thereon, a lift member normally holding said reproducer out of engagement with said record and having a notch to locate said reproducer in initial position above the beginning of said recording, an inclined side on said notch, and means operable by said shaft to lower said lift member whereby said reproducer is lowered into engagement with said record at the beginning of said recording and to subsequently raise said lift lever, said inclined side engaging said reproducer to lift the same from said record at the end of said recording and to guide said reproducer to initial position in said notch.

49. In combination, a support, a driving motor secured thereto having a vertical shaft, a record support driven by said shaft, a record carried by said support, a reproducer arm pivotally mounted on said support, and having a reproducer at its outer end adapted to engage said record, said arm being radially and vertically movable, a horizontal shaft driven by said motor, a cam on said horizontal shaft, means operated by said cam to raise and lower said reproducer arm relative to said record, and means to cause said arm to return to a predetermined position during the period it is lifted from the record.

JOHN J. SHIVELY.

HARRY R. VAN DEVENTER.
